FOLDING CHAIR

Frank J. Leverone, Medford, Mass.

Application February 16, 1935, Serial No. 6,907

2 Claims. (Cl. 155—81)

This invention relates to chairs, and its general object is to provide a folding chair that is designed for attachment to a desk, counter, table or any suitable attaching means that is capable of holding and partially supporting the same, and the chair may or may not be used therewith, but is always handy and convenient to be unfolded and utilized in its intended capacity as a comfortable seating device.

10 A further object of the invention is to provide a chair that can be folded or unfolded in an easy and expeditious manner, and when in position for use, cannot tip, slide, collapse or fold up, with or without weight thereon.

15 Another object of the invention is to provide a chair of the foldable type and character set forth, that is light in weight, so as to be easy to handle, yet is capable of supporting maximum weight, is simple in construction, inexpensive to manufacture, easy to install, and extremely efficient in use and service.

This invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

Figure 1 is a view illustrating my chair attached to a desk.

Figure 2 is a side view of the chair showing it partially folded.

Figure 3 is a perspective view, with the chair partially folded.

Figure 4 is a sectional view taken approximately on line 4—4 of Figure 1.

40 Figure 5 is a fragmentary view of one type of hinge joint between the seat and back rails or legs.

Figure 6 is a similar view of another type of hinge joint.

45 Referring to the drawing in detail, it will be noted that I have illustrated my chair as being attached to a desk, but I want it understood that it can be attached to any type of furniture, counter, table, or any suitable means, to be or not to be associated or used therewith. While the chair is shown as being attached to a desk, the latter acts merely in the capacity as an attaching, holding and partial supporting means therefor and so that the chair will be in a convenient place to and always handy for the user of the desk to

converse with a person, such as during an interview or the like.

5 My chair includes rear rails providing leg portions 1 and back portions 2 and these portions diverge rearwardly with respect to each other as best shown in Figure 1. The rails are held in spaced parallel relation with respect to each other through the instrumentality of cross members 3, and while the single cross member 3 is provided for cooperation with the back portions to form 10 the back of the chair, and that member is arranged adjacent the upper ends of the back portions, it will be obvious that any number of cross members may be employed and in fact the entire back of the chair may be solid.

15 The lower cross member extends from the point of juncture with the leg portions 1 with the back portions 2 and secured to the lower cross member adjacent to one end thereof through the medium of the hinge 4 is a seat rail 5 which is to be attached to any suitable means, such as a desk as shown, by a hinge 6.

The seat 7 of my chair is preferably hinged to the back portions 2 adjacent to their juncture with the leg portions and I have illustrated two 25 types of hinges for that purpose, the preferred form being best shown in Figure 5 and which is generally referred to as being a rule type hinge, in that it includes leaf portions 8 and 9, the leaf portions 8 being countersunk in the back portions 30 and the portions 9 being countersunk in the seat and have pintles 10 extending laterally therefrom and journaled in bearing ears 11, therefore it will be seen that lateral movement of the seat is practically impossible.

35 Regardless of what type of hinge is used to secure the seat to the rear rails the latter are recessed to accommodate the rear end portions of the seat, when the latter is in position for use and these recesses are indicated by the reference 40 numeral 12.

45 The other type of hinge for securing the seat to the rear rails includes a leaf 13 that is shaped to follow the recess 12 and is fixed therein, with a hinge barrel secured to the upper portion thereof, and the companion leaf 14 follows the shape of the rear end portions of the seat, and countersunk therein. The upper extension of the leaf 14 is provided with hinge barrels 15 for cooperation with the hinge barrel of the leaf 13, and of 50 course a pin passes through the companion hinge barrels for securing the leaves 13 and 14 together. The leaves 14 are fixed to the seat and the lower extending portion thereof underlies the seat, as clearly shown in Figure 6. It will 55

be noted that the lower ends of the recesses 12 are curved downwardly so as to allow fitting of the hinge portions on the seat therein and free movement of the seat with respect thereto.

5 A seat rail 16 is hingedly secured to the forward portion of the seat and is disposed transversely thereof as best shown in Figure 3. Fixed to one end of the seat rail 16 is a leg 17 and this leg is connected to the adjacent rear leg through 10 the instrumentality of a link 18 that has its forward end pivoted to the leg 17 and its rear end pivotally connected to a projection 19 that is fixed to the rear leg portion.

The seat rail 5 is provided with a dovetail 15 groove or notch 20 adjacent its forward end and in its upper surface for the purpose of receiving a dovetail tongue 21 when the chair is in open or unfolded position as shown in Figure 1, with the result, when the chair is in the position 20 last mentioned, it is positively held and cannot tip, slide, collapse or fold up, with or without weight thereon, yet the chair is capable of being disposed to either folded or unfolded positions, in an easy and expeditious manner, and the 25 manner of disposing the chair to these respective positions is obvious in the drawing.

It is thought from the foregoing description that the advantages and novel features of my 30 invention will be readily apparent.

I desire it to be understood that I may make 35 changes in the construction and in the combination and arrangement of the several parts, provided that such changes fall within the scope of the appended claims.

What I claim is:

1. A foldable chair comprising rear rails including leg and back portions, cross members bridging the rear rails, means having one end hingedly secured to one cross member and the other end to a suitable support respectively, said rear rails being recessed, a seat hingedly secured to the rear rails and arranged to have its rear end received in the recesses when the chair is in open position, a seat rail hingedly secured to the underside of the seat, a dovetail joint included in the seat rail and the first mentioned means for securing the chair in open position, a leg depending from the seat rail and cooperating with the leg portions and support for supporting the chair in open position, and pivotally mounted brace means connected to the leg and one leg portion. 5 10 15

2. A foldable chair comprising a rear portion 20 including legs, a seat pivotally secured to the rear portion, a notched rail having one end secured to the rear portion, supporting means having the opposite end of the rail secured thereto, said rail mounted for movement in a horizontal plane into 25 and out of the path of one side of the under surface of the seat, legged means hinged to the seat and having an end received in the notch of the rail for cooperation with the latter, the supporting means, and the legs of the rear portion 30 and legged means respectively for supporting the seat in operative position a suitable distance from the floor, and brace means pivotally secured to said legged means, and a leg of the rear portion. 35
